Fig. 1

Fig. 2

The two sides of the baptismal font not shown in Figure 1 are the same as the two sides which are shown.

I claim:

The ornamental design for a baptismal font, substantially as shown and described.
